UNITED STATES PATENT OFFICE

168,222

BLANKET HOLDER

Katsumi Gus Harano, Los Angeles, Calif.

Application December 20, 1951, Serial No. 17,784

Term of patent 14 years

(Cl. D17—6)

To all whom it may concern:

Be it known that I, Katsumi Gus Harano, a citizen of the United States, residing at Los Angeles, in the county of Los Angeles and State of California, have invented a new, original, and ornamental Design for Blanket Holder, of which the following is a specification, reference being had to the accompanying drawing, forming part thereof.

In the drawing:

Fig. 1 is a front elevational view of a blanket holder, showing my new design; and

Fig. 2 is a side elevational view thereof.

I claim:

The ornamental design for a blanket holder, substantially as shown.

KATSUMI GUS HARANO.
